(57) **CLAIM**

The ornamental design for a window component for a roof window installation, as shown and described.

DESCRIPTION

FIG. 1 is a front elevational view of a first embodiment of the window component for a roof window installation showing our design;

FIG. 2 is a top plan view of the window component for a roof window installation;

FIG. 3 is a left side elevational view of the window component for a roof window installation;

FIG. 4 is a rear elevational view of the window component for a roof window installation;

FIG. 5 is a perspective view taken from the front, top and left side of the window component for a roof window installation;

FIG. 6 is a front elevational view of a second embodiment of the window component for a roof window installation;

FIG. 7 is a top plan view of the window component for a roof window installation;

FIG. 8 is a left side elevational view of the window component for a roof window installation;

FIG. 9 is a rear elevational view of the window component for a roof window installation;

FIG. 10 is a perspective view taken from the front, top and left side of the window component for a roof window installation;

FIG. 11 is a front elevational view of a third embodiment of the window component for a roof window installation;

FIG. 12 is a top plan view of the window component for a roof window installation;

FIG. 13 is a left side elevational view of the window component for a roof window installation;

FIG. 14 is a rear elevational view of the window component for a roof window installation; and,

FIG. 15 is a perspective view taken from the front, top and left side of the window component for a roof window installation.

The right side of each of the embodiments of FIGS. 1, 6 and 11 is a mirror image of the left side.
